COMPREHENSIVE INFANT CARE SYSTEM

John W. Beld, O'Fallon, Warren G. Kinninger, Florissant,
Robert E. N. Klohr, Fenton, and Paul A. Byrne, St.
Louis, Mo., assignors to Puritan-Bennett Corporation,
Kansas City, Mo.

Original design application Ser. No. 293,653, Sept. 29,
1972, now Pat. No. 236,165. This application Apr. 11,
1975, Ser. No. 567,181

Term of patent 14 years

Int. Cl. D24—01

U.S. Cl. D83—1 G

FIG. 1

FIG. 2

FIG.3

FIG. 4

FIG. 1 is a top plan view of a comprehensive infant care system showing our new design;

FIG. 2 is a front elevation view of FIG. 1;

FIG. 3 is a right side elevation view of FIG. 2; and

FIG. 4 is a perspective view thereof.

This is a division of design application Ser. No. D. 293,653, filed Sept. 29, 1972, and now Pat. No. D. 236,165.

We claim:

The ornamental design for a comprehensive infant care system, as shown.
